UNITED STATES PATENT OFFICE.

BARNET R. RAPP, OF WESTCHESTER, PENNSYLVANIA, ASSIGNOR TO
HIMSELF AND WILLIAM H. LAWSON, OF SAME PLACE.

IMPROVEMENT IN THILL-COUPINGS.

Specification forming part of Letters Patent No. **142,274**, dated August 26, 1873; application filed
May 6, 1873.

To all whom it may concern:

Be it known that I, BARNET R. RAPP, of Westchester, Chester county, Pennsylvania, have invented an Improvement in Thill-Couplings, of which the following is a specification:

The object of my invention is to improve the thill-coupling, for which Letters Patent No. 124,159 were granted to myself and Wm. H. Lawson, assignee, on the 27th day of February, 1872; and my improvement consists in dispensing with the long arm of the cam-lever D, described in the said patent, and substituting therefor a socket, e, for the reception of the end of a lever, E, as shown in the side view, Fig. 1, of the accompanying drawing.

A represents the carriage-axle; B, a clip passing around the same; C, an extension-plate secured to the clip D, the cam-lever jointed to the outer end of the extension-plate by a pin, a, and arranged, when turned up, as shown in the drawing, to bear against an elbow-plate, F, and thus compress a block of rubber, G, between the said elbow-plate and the thill H, which is jointed to ears d on the clip by a pin retained in place by arms f on the cam-lever, all as described in the said patent, in which, however, the cam-lever was provided with, and operated by, a long permanent arm, the latter being more or less unsightly and in the way. In place of this permanent arm on the cam-lever, I form on the latter a socket, e, for the reception of the end x of a lever, E, the

said end x being toothed or serrated so that it can retain its hold in the socket. By depressing this lever E the cam-lever may be turned to the position shown by dotted lines, thereby relieving the thill from the pressure of the rubber-block G, and at the same time uncovering the ends of the pin which connects the thill to the ears d d, and permitting the said pin to be withdrawn. By the same lever E the cam-lever may be readily restored to its original position when the shafts of the vehicle have been readjusted to the coupling, after which the end of the lever E may be withdrawn from the socket e of the cam-lever and deposited in a suitable place ready for use. I prefer to make the lever E with a transverse handle, y, at its outer end, so that this handle may be used as a hammer-head to drive out the pin which connects the thill to the ears d, should there be any difficulty in removing said pin.

I claim as my invention—

The clip D, having a socket, e, for the reception of the end of a detachable lever, E, as and for the purpose set forth.

In testimony whereof I have signed my name to this specification in the presence of two subscribing witnesses.

BARNET R. RAPP.
